INVENTOR
CHARLES MILLER
BY *Carl W. Loken*
ATTORNEY

UNITED STATES PATENT OFFICE.

CHARLES MILLER, OF LONG ISLAND CITY, NEW YORK.

SHOE LAST.

Application filed April 25, 1927. Serial No. 186,292.

This application is a continuation in part of my application Serial No. 20,435, filed April 3, 1925, for protective attachment for shoe lasts and the invention relates to a last 5 for use in connection with the manufacture of shoes.

It has been proposed heretofore to attach the heel to the shoe by means of a screw member passing through the heel portion of 10 the last, which member is screwed into the heel to hold the same in position during the time interval necessary for the drying of the adhesive used. See United States Patent No. 1,527,168, of February 24, 1925. It has 15 been found in actual practice, however, that the high pressure exerted upon the rear heel portion of the last causes a great deal of breakage of lasts, and therefore, the cost of manufacture of shoes in accordance with this 20 process is so high as to render the same impractical.

The use of the screw member for attaching heels is highly desirable, for the reason that with other known methods, the shoe 25 must lie idle for approximately twelve hours, which is the time necessary for the adhesive to dry; whereas, when the screw member is used, the process of manufacture of the 30 shoes may be carried on while the adhesive is drying.

Also, during the lasting of turn shoes, the operator has occasion to pound the upper edge of the heel portion of the last upon a hard surface. This causes a further loss 35 of lasts due to chipping and breakage at the rear heel portion.

It is, therefore, an object of this invention to produce a last which will withstand the various stresses exerted upon it during the 40 process of manufacturing shoes.

In connection with the lasting of the upper the operator must measure by means of some measuring tape or the like, the distance from the heel seat to the top edge of the upper 45 at the heel portion. This measurement determines to a great extent the fit of the shoe, particularly at the edge of the vamp which, contacts with the instep of the wearer's foot. If the shoe is lasted too low, 50 the vamp will cut the wearer's instep. On the other hand, if the upper is lasted too high, the edge of the upper will cut the wearer's ankle at the rear above the heel. It will thus be seen that the measurement 55 during lasting must be done carefully and accurately. Also, in connection with the

manufacture of turn shoes, there are two lasting operations, and therefore, two measuring operations.

It is a further object of this invention to 60 provide a gaging means on the last which eliminates the necessity for separate measuring operations and which makes possible a more uniform lasting operation.

These and other objects of the invention 65 will be readily apparent to one skilled in the art from the following description, taken in connection with the accompanying drawing, in which:

Figure 1 is a fragmentary sectional view 70 of a last embodying my invention.

Figure 2 is a side elevation of a last embodying a modified form of this invention. Figures 3 and 4 are rear elevational views 75 of the lasts shown in Figures 1 and 2 respectively.

Figure 5 is a perspective view of the cap shown in Figure 2.

Referring in detail to the drawing the last 10 which may be of any suitable form, 80 and which may be provided with the thimble hole 12 for the reception of the jack pin, is further provided with a cap member 14 covering the top of the heel portion of the last. The cap 14 has the downwardly extending 85 portion 14* which embraces the rear and side portions of the last as shown. The cap 14 is formed of any suitable hard metal or alternatively it may be formed of a non-metallic substance harder than the wood material of which lasts are constructed. Materials such as bakelite and other phenol condensation products or fibre compositions have been found to be suitable in this connection. 90

Alternatively the cap 14 may be formed solid as shown in Figures 2 and 4, the upper portion of the last being cut away to receive this member. 95

A layer 16 of relatively yieldable material such as sole leather, for example, is placed between the last and the cap 14. A hole or aperture 18 extends from the top to the bottom of the heel portion of the last, to permit the use of a screw member for the 100 purpose of holding the heel in place during the process of attaching the same to the shoe. A suitable metallic lining 20 is formed interiorly of the hole 18 for the purpose of 105 protecting the last from being cut by the threads of the screw holding means, and also from being cut by the drill member used to 110

drill the hole in the heel prior to the insertion of the screw member, it being understood that the heel is drilled while in position on the last.

5. It will thus be seen that the cap 14 with the extension 14^a protects the heel portion of the last from breaking or chipping both at the rear and at the sides adjacent thereto.

During the lasting of the upper it is necessary to tack the same to the last temporarily.

10. I, therefore, provide the slot at the rear portion of the extension 14^a, and insert a wooden plug 24 in this slot, thus providing a tack receiving portion at the rear of the heel portion of the last. Obviously the slot 22 may be of any suitable size or configuration and the plug 24 may be of any material suitable to receive lasting tacks.

Now, as explained heretofore, it is necessary to properly position the edge of the upper at the rear of the heel portion during the lasting operations. In order to guide the operator, and render the product uniform, I provide the markings 26, 28, and 30 cut in

25 the rear of the cap 14. Thus for example, the marking 30 would indicate first lasting and the marking 26 would indicate the second lasting. It is then merely necessary for the operator to position the upper properly 30 with respect to these indicating marks and a uniform product will be assured, insofar as the lasting at the rear is concerned. Also, the prevalent disadvantage of cutting the wearer's foot at the instep in connection with

35 ladies' slippers will be eliminated. The line 32 is provided to properly position the upper with respect to the last in a lateral direction. It will be understood, of course, that any predetermined arrangement of markings may be 40 provided, depending on the particular type of shoes being made.

While I have disclosed a specific embodiment of the invention, it is to be understood that many alterations and changes will readily suggest themselves to those skilled in the art. I, therefore, do not intend to be limited by the details of structure except as defined 45 in the appended claims.

Having thus described my invention I de-

sire to claim and secure by Letters Patent 50 of the United States:

1. A wooden last for shoes, said last being provided with a jack pin recess and an aperture extending from the top to the bottom at the heel portion thereof, a protective cap attached to the top of the heel portion of said last, and an extension formed on said cap at the side and rear portions of the last, said cap having an aperture in alignment with said aperture in the last, whereby said cap 60 forms an entrance to said aperture, said entrance being of a material harder than the material of said last.

2. A last for shoes, said last being provided with a jack pin recess and an aperture extending from the top to the bottom at the heel portion thereof, a protective cap attached to the top of the heel portion of said last, said cap having an aperture in alignment with said aperture in the last, an extension formed on said cap at the side and rear portions of the last, and nail receiving means carried by said extension.

3. A wooden last for shoes, said last being provided with a jack pin recess and an aperture extending from the top to the bottom thereof, a protective plate of a material harder than the material of which the last is constructed, said plate having an aperture in line with the aperture in the last, an extension formed on said plate at the rear and side portions, and means carried by said plate to serve as a guide in the lasting operation of shoe manufacture.

4. A wooden last for shoes, said last being provided with a jack pin recess and an aperture extending from the top to the bottom thereof, a protective plate of a material harder than the material of which the last is constructed, said plate having an aperture in line with the aperture of the last, an extension formed on said plate at the rear and side portions, means carried by said plate to serve as a guide in the lasting operation of shoe manufacture, and means carried by said extension to receive tacks or nails.

CHARLES MILLER.
